UNITED STATES PATENT OFFICE.

EARNEST R. HOPKINS, OF KANSAS CITY, MISSOURI.

WEATHER STRIP.

Application filed August 2, 1926. Serial No. 126,624.

My invention relates to improvements in weather strips and my principal object is to provide a new and useful device of this character which can be readily applied to doors and windows for the purpose of excluding drafts, dust and rain, and preventing said doors and windows from rattling.

Another object is to provide resilient parting strips which coact with the weather strips in excluding drafts, dust and rain, and preventing the sash from rattling.

A further object of my invention is to provide spring means for assisting in raising the window sash.

In order that the invention may be fully understood, reference will now be had to the accompanying drawing, in which:

Fig. 1 shows the invention applied to a pair of window sash.

Fig. 2 is an enlarged fragmentary cross section on line 2 of Fig. 1.

Fig. 3 is an enlarged fragmentary vertical section on line 3—3 of Fig. 1.

Fig. 4 represents one section of the window strip ready for assembly.

Referring in detail to the different parts, 2 designates a housing which is preferably in the form of a channel bar. 4 designates a rigid bar preferably of hollow rectangular cross section and adapted to fit loosely within the housing 2. 6 designates a plurality of springs adapted to be interposed between the housing 2 and the bar 4 to press the latter outwardly against the window frame C.

In order to install the weather strip grooves 8 are formed in the top and side rails of an upper sash as A, while similar grooves are formed in the bottom and side rails of the lower sash B to receive the housings 2, which are fitted snugly within said grooves. The rigid bars 4 with the springs 6 assembled upon fastening devices 10, such as screws or nails, are then placed within the housings 2, which have holes to permit the fastening devices 10 to be driven into the sash and thus hold the housings 2, the bars 4 and the springs 6 in assembled position. When thus installed it is apparent that the springs 6 will press the associate bars 4 outwardly against the adjacent surfaces of the window frame C and thereby exclude dust and rain and prevent the sash from rattling.

In order to prevent the heads of the nails or screws 10 from contracting the adjacent

portions of the window frame C, the outer holes 12 provided in the bars 4 for said nails or screws 10 are of sufficient diameter to allow the heads of said nails or screws to be driven inwardly against the inner portions of said bars 4, as shown more clearly by Figs. 2 and 4. The joint between the meeting rails D and E of the sash A and B, respectively, may be also rendered rattle and weather-proof by supplying one of said meeting rails with a weather strip, as shown by dotted lines Fig. 1, and full lines Fig. 3.

The joints between the side rails of the window sash A and B and the adjacent portions of the window frame C are further rendered rattle and weather-proof by parting strips 14 consisting of resilient channel bars which are installed in grooves 16 in said frame C and have their free ends 18 pressing against the sash A and B.

In lieu of the ordinary sash cords and weights for counterbalancing the weight of the sashes A and B to assist in raising the latter, I provide coil springs 20, which are arranged in grooves 22 and 24 in the side rails of the sash A and B and secured at their lower ends to the respective sash by suitable fastening devices 24^a and at their upper ends to the frame C through the intermediary of suitable fastening means such as screw eyes 26.

While I have shown and described the preferred construction and arrangement of my invention I reserve the right to all such changes and modifications as properly fall within the spirit and scope of the invention as claimed.

Having thus described my invention, what I claim and desire to secure by Letters Patent, is:

A device of the character described consisting of channel bars of the same length as and adapted to be installed in grooves formed in edges of the window sash, bars of hollow rectangular cross section movably mounted in said channel bars, spring means interposed between the channel bars and said rectangular bars to force the latter against the window frame, and means for holding said bars and said spring means in assembled position in the window sash consisting of a plurality of elements extending loosely through the rectangular bars and the channel bars and firmly secured in the window sash.

In testimony whereof I affix my signature.
EARNEST R. HOPKINS.
